UNITED STATES PATENT OFFICE.

MICHAEL C. HARNEY, OF ST. LOUIS, MISSOURI, ASSIGNOR OF ONE-HALF TO
WILLIAM N. BRENNAN AND ANN BRENNAN, BOTH OF SAME PLACE.

SEAL-LOCK.

SPECIFICATION forming part of Letters Patent No. 351,030, dated October 19, 1886.

Application filed January 25, 1886. Serial No. 189,694. (Model.)

To all whom it may concern:

Be it known that I, MICHAEL C. HARNEY, of the city of St. Louis, in the State of Missouri, have invented a certain new and useful 5 Improvement in Seal-Locks, of which the following is a full, clear, and exact description, reference being had to the accompanying drawings, forming part of this specification, and in which—

10 Figure 1 is a side view of my improved seal-lock. Fig. 2 is a perspective view of the lower end of the bolt with the seal removed. Fig. 3 is a similar view with the seal in place on the bolt. Fig. 4 is a longitudinal section of the 15 seal-lock, showing part of the end of the bolt, the section being taken on the line 4 4, Fig. 5. Fig. 5 is a similar view taken on line 5 5, Fig. 4.

My invention relates to an improved seal-lock, intended more particularly for railway-cars; and my invention consists in features of 20 novelty, hereinafter fully described, and pointed out in the claims.

Referring to the drawings, A represents 25 part of the car-body, and B part of the car-door, the former being provided with a staple, D, as usual, and the latter with a hasp, E, as usual.

F represents a locking-bolt, connected to 30 the car-body by a chain, G, and adapted to fit through the staple, as shown. The lower end of the bolt has an extension, H, provided with an inclined tongue or projection, I, between the inner end of which and the end of 35 the bolt is a space, J. The end of this extension H is reduced, as shown, forming a shoulder, L, beyond which is an extension or lip, M.

N represents the seal, which consists of a 40 sleeve or thimble, having a loop, O, secured to the outer end, which is preferably made of wire. The inner end of the sleeve is opened, so that it (the sleeve) can be slipped over the end of the bolt, as shown, and the outer end is closed, with the exception of a small opening, P, to receive the extension or lip M of 45 the bolt.

In applying the seal it is slipped over the

end of the bolt, as shown in Figs. 1, 3, 4, and 5, the loop O slipping upward and over the inclined projection I. When the seal has been 50 forced entirely onto the bolt, the spring-loop O, having passed the inner end of the extension I, springs down into a horizontal position, as shown in Fig. 5, and thus being engaged over the end of the projection, the seal 55 cannot be removed without destroying it. The seal has a projection or protuberance, Q, to prevent the bolt from being withdrawn from the staple until the seal is removed therefrom. The lip or extension M, fitting in the 60 opening P of the end of the seal, prevents the seal from being turned on the bolt, and thereby avoids all possibility of the loop being disengaged from the projection I by turning the seal. The seal may have a tablet, T, as shown 65 in Fig. 1, upon which may be marked the station to which the car is to be sent.

I claim as my invention—

1. The combination of a bolt provided with a locking projection and a seal consisting of 70 a sleeve provided with a loop to engage over the projection on the bolt, substantially as shown and described.

2. A bolt having a reduced end and lip, in combination with a seal consisting of a sleeve 75 provided with a loop and an opening to receive the lip on the bolt, substantially as shown and described.

3. The combination of a bolt having a reduced end, inclined projection on the reduced 80 end of the bolt, sleeve having a protuberance, Q, and spring-loop secured to the outer end of the seal, substantially as set forth.

4. The combination of the bolt having a reduced end, provided with a lip, M, inclined 85 projection on the reduced end, and seal consisting of a sleeve having a protuberance, Q, and closed end provided with an opening, P, and a spring-loop secured to the end, all substantially as and for the purpose set forth.

MICHAEL C. HARNEY.

In presence of—

GEO. H. KNIGHT,
EDW. S. KNIGHT.
